Primary Examiner — Cynthia Ramirez*Assistant Examiner* — Jeremy S. Swartz(74) Attorney, Agent, or Firm — Olive Law Group, PLLC(57) CLAIM

The ornamental design for an under shelf basket, as shown and described.

DESCRIPTION

FIG. 1 is a top, front, left side perspective view of an under shelf basket showing my new design;

FIG. 2 is a bottom, rear, right side perspective view thereof;

FIG. 3 is a bottom, front, left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a top, front, left side perspective view showing the under shelf basket in an extended state; and,

FIG. 11 is an enlarged view of portion 11 in FIG. 2.

The evenly dashed broken lines illustrate features of the under shelf basket that form no part of the claimed design. The unevenly dashed broken lines define the boundary of an enlarged view and form no part of the claimed design.
